BICYCLE FRAME

William F. Jacoby and Charles E. Kerr, Little Rock, Ark.,
assignors to American Machine & Foundry Company,
a corporation of New Jersey

Filed Mar. 10, 1969, Ser. No. 16,166

Term of patent 14 years

Int. Cl. D12—11

U.S. Cl. D90—8

FIG. 2

FIG. 1

FIG. 3

FIG. 4

FIG. 1 is a perspective view of a bicycle frame showing our design;

FIG. 2 is a side elevation view of the bicycle frame;

FIG. 3 is a fragmentary perspective view of a modified form thereof, it being understood that the remainder is the same as shown in FIGS. 1 and 2; and

FIG. 4 is a fragmentary perspective view of another modified form thereof, it also being understood that the remainder is the same as shown in FIGS. 1 and 2.

We claim:

The ornamental design for a bicycle frame, substantially as shown and described.
